L. APRILE

UNIVERSAL SQUARE :

Filed Aug. 5, 1921

Inventor:
Louis Aprile
By James V. Randay
Attorney.

UNITED STATES PATENT OFFICE.

LOUIS APRILE, OF CINCINNATI, OHIO.

UNIVERSAL SQUARE.

Application filed August 5, 1921. Serial No. 490,120.

To all whom it may concern:

Be it known that I, LOUIS APRILE, a citizen of the United States, residing in the city of Cincinnati, in the county of Hamilton and State of Ohio, have invented certain new and useful Improvements in Universal Squares, of which the following is a specification.

My invention relates to universal squares employed for marking and laying off joints and designs on irregular surfaces, and more particularly on cornice work, copings, mouldings, ornamental stone work and the like.

Heretofore considerable trouble has been experienced in laying of mouldings, corner work and the like having irregularly formed surfaces and outlines, for the reason that no satisfactory means have been devised for accurately drawing lines in a given plane so that these cornices or mouldings may be afterwards cut and accurately joined together.

My invention has for its object the provision of a device adapted for readily marking and laying off marble and wood work, and more particularly work such as cornices, mouldings, and those having irregular surfaces.

My invention consists of a base having a guiding blade universally mounted thereon, so as to be adjustable in any direction; further, in adjustable marking means adapted to be guided by said guiding blade; further, in positioning and clamping means for the guiding blade; and further, in means for locating and guiding the base.

My invention further consists in the parts and combination and arrangement thereof, as herein described and claimed.

In the drawing:

Fig. 1 is a perspective view of my improved device showing the manner of employing the same in laying off a moulding.

Fig. 2 is a plan view of the device;

Fig. 3 is a side elevation of the same partly broken away;

Fig. 4 is a vertical cross section of part of my improved device taken on the line 4-4 of Fig. 2 with the outer end of the 50 guiding blade broken away;

Fig. 5 is a similar view taken on the line 5-5 of Fig. 2;

Fig. 6 is a plan view of my improved device showing the auxiliary base attached, 55 and having the blade removed;

Fig. 7 is a side elevation of the same partly broken away; and

Fig. 8 is a perspective view of the auxiliary base.

In the embodiment of my invention as illustrated, a base 10 has rotatably mounted thereon a post 11 as by a trunnion 12 journaled in a hole 13 of the base. The post has a flange 14 thereon adapted to rest on the base 10, and is received in circular rabbet 15 formed in a retaining ring 16 secured to the base by screws 17. The ring 16 has an inwardly projecting flange 18 thereon received in a circular rabbet 19 on the flange 70 14 on the post. A clamp screw 25 has threaded connection 26 with the inwardly projecting flange 18, and is adapted to exert pressure against the flange 14 on the post and serves to clamp the same in adjusted 75 position.

The base further has a depending apron 27 thereon which serves as a guide for locating the main base with reference to an edge of the material upon which the device 80 may be employed.

The post has a slot 30 therein in which a guiding blade 31 is clamped as by a clamp screw 32 passing through a hole 33 in portion 34 of the post, and having threaded 85 connection 35 with portion 36 of the post.

The blade preferably comprises an arm 37 having a depending plate 38 thereon. The arm 37 has a slot 39 therein extending in the direction of its greatest length 90 through which the clamp screw 32 passes, when the guiding blade has its arm clamped in the post. I prefer to form a hole 40 in the plate 38 of the guiding blade, so as

to cause the same to be capable of being clamped in the post 11 with the arm extending outwards.

In order that it will be possible to scribe 5 a line in a given plane over any irregular surface I provide a scribing device 45 adapted to be guided by the guiding blade 31. The scribing device comprises a pair of pivotally connected arms 46 pivoted as by a 10 pivot 47. An arc piece 48 secured to one of the arms as by a pin 49, is slidable in a slot 50 in the other of the arms and clamped in adjusted position by a thumb screw 51. One of the arms has a bent portion 52 thereon, 15 to which a guide piece 53 is secured as by rivets 54. The other of the arms has a block 55 thereon, having a hole 56 therein in which a marking point 57 is adjustably secured as by a clamp screw 58.

20 Means are provided whereby the plane of the guiding blade may be centered with relation to circular projections or corners on the surface upon which it is desired to lay off lines. Thus an auxiliary base 60 has a miter 61 therein, formed by wings 62 and 63. A clearance slot 64 at the base of the miter provides clearance for sharp corners on the work. The auxiliary base is of substantially the same thickness as the height of 25 the depending apron 27. The auxiliary base is adapted to be secured below the main base and having its side edges coinciding with the side edges of the base 10. The auxiliary base has pins 65 thereon which are 30 frictionally received in holes 66 in the base 10. The pins 65 and the holes 66 are so located with reference to the post 11 that a medial line passing through the corner of the miter will pass through the axial center 35 of the post and also cause the miter 61 to project clear of the base 10.

40 The base 10 and the depending apron 27 thereon have openings 67 therein so that a line may be scribed to the corner of the work, 45 it being sometimes necessary to meet another line previously scribed on adjacent surfaces.

In use we will assume that it is desired to 50 scribe an angular line on the irregular surface 68 of a section of moulding 69, as shown in Fig. 1. The guiding blade 31 is adjusted to an angle corresponding to the angle of cut it is desired to make, by rotating the post 11 and the flange 14 on the base 10 and clamping the same in adjusted position by 55 the clamp screw 25. The base 10 is located in position by contacting the edge of the work with the depending apron 27. The guiding blade 31 is clamped in adjusted position in the slot 30 by the clamp screw 32 60 in such manner as to cause the depending plate 38 to extend downwardly and over the irregular surface of the moulding, as shown in Fig. 1. The flange 14 may have a mark 65 thereon adapted to coact with marks 91 on the retaining ring 16. The marks 91 may

be spaced radially at regular intervals to form an index of angles in degrees of a circle. Figure designations 92 may be placed at the marks 91 to indicate the number of degrees the said marks are spaced from a given point for instance a zero point such as indicated at 93. The marks 91 therefore serve to indicate the angle in degrees at which the guiding blade may be set with respect to a predetermined plane. The marking device 45 may now be employed to scribe a line by placing the face of the guide piece 53 into entire contact with the guiding blade. The marking point 57 is placed in contact with the surface of the moulding through one of the openings 67, the pivotally connected arms 46 being previously adjusted and clamped in position through the medium of the arc piece 48 and clamp screw 51. The desired line may now be scribed by causing the marking point to follow the irregular surface of the moulding while simultaneously holding the guide piece 53 in contact with the guiding blade. The marking point in this manner is caused to follow in a given 85 plane the intricate and irregular surface of the work.

The guiding blade being slidably and pivotally mounted on the base may be adjusted and clamped in any desired position to 90 scribe lines on any irregular or plane surface. The guiding blade may be adjusted to suit any particular outline of the surface upon which it is desired to scribe a line. The auxiliary base is removed in the operation 95 previously described as it is only necessary to employ the same when scribing lines on surfaces of work having no straight edges.

100 Should it become necessary to scribe a line at any given angle radially or tangentially to a circular projection located on a smooth surface, the auxiliary base is placed in a position, as shown in Figs. 6 and 7. The base is brought forward so as to cause 105 the wings 62 and 63 of the miter 61 to contact the circular projection. This locates the base 10 in the desired position. The guiding blade or arm is then adjusted and the line scribed as hereinbefore explained.

110 What I claim as new and desire to secure by Letters Patent is:

1. In a universal square, a base having a positioning straight edge provided with clearance openings or notches therein, a 115 guiding blade, means mounting said blade, marking means adapted to be guided by said blade and having a marking point adapted to scribe a line to the edge of the work in said clearance openings or notches, substantially as set forth and for the purposes specified.

2. In a universal square, a base, a vertical post pivotally mounted adjacent said base, a plate pivotally mounted on said post, a 120

- pair of pivotally connected arms, a marking point adjustable longitudinally on one of said arms and a guide fixed on the other of said arms and adapted to engage said 5 plate and slide thereon.
3. In a universal square, a base, an auxiliary base detachably mounted on said first named base and having a notch adapted to provide clearance on sharp corners of the 10 work, a guiding blade on said first named base and marking means guidable by said guiding blade whereby a line may be scribed on irregular surfaces in a given plane parallel to said guiding blade and a distance 15 therefrom.
4. In a universal square, a base having a hole therein and one edge of said base being straight, a post, a trunnion on said post rotatable in said hole, a circular flange 20 on said post above said trunnion adapted to have bearing on said base, a circular ring secured on said base over said flange, said ring having a rabbet therein in which said flange seats for rotatably securing the flange 25 to the base, a clamp screw for clamping said flange to said ring, clamp screws for clamping said ring to said base, said post having a slot therein at right angles to the plane of rotation thereof, a guiding blade 30 slidably and pivotally adjustable in said slot, a clamp screw for clamping said blade in adjusted position and adjustable marking means adapted to be guided by said 35 guiding blade.
5. In a universal square, a base having a hole therein and one end of said base being straight, a post, a trunnion on said post rotatable in said hole, a circular flange on 40 said post above said trunnion and adapted to have bearing on said base, a circular ring secured on said base over said flange, said ring having a rabbet therein in which said flange seats for rotatably securing the flange 45 adjacent the base, a clamp screw in said ring adapted to be received against said flange, whereby said post is adapted to be clamped in adjusted position relative to 50 said ring, said post having a slot therein at right angles to the plane of rotation thereof, a guiding blade slidably and pivotally adjustable in 55 said slot and comprising an arm, a depending portion integrally formed therewith and said arm having a slot therein, said post having a hole therethrough transversely of said slot, a clamp screw 60 passing through said last named hole and the slot in said arm and having threaded connection with said post and marking means adapted to be guided by said guiding blade.
6. In a universal square, a base having one edge straight whereby said base is capable of being positioned with relation to the edge of the work, a post rotatably 65 mounted in said base, a flange on said post 70 and having an indicating mark thereon, a circular ring secured to said base and having angle index marks thereon and having a rabbet therein in which said flange is rotatably retained, a clamp screw extending 75 through and threaded to said ring whereby said flange and post are clamped in adjusted position relative to said ring and base, said post having a slot therein at right angles to the plane of rotation thereof, a 80 guiding blade slidably and pivotally mounted in said slot, a clamp screw in said post adapted to engage said blade whereby said blade is clamped in adjusted position, an adjustable marking device adapted to be 85 guided by said blade and comprising a pair of pivotally connected arms, a segment on one of said arms the other of said arms having a slot therein in which said segment is 90 slidably, a clamp screw for clamping said segment in said slot whereby said arms are held in adjusted position relative to each other, a marking point on one of said arms and a guiding disc on the other of said arms adapted to coact with said 95 guiding blade.
7. In a universal square, a base having angularity indicating means mounted thereon and having a straight edge, an auxiliary base detachably mounted on said first named base and having spaced apart wings thereon and having a miter opening or notch intermediate said wings, said first named base having a plurality of holes therein, pins 100 on said auxiliary base frictionally receivable in said holes and so located as to hold said auxiliary base on said first named base, a guiding blade connected with said first named base and adjustable to any position about an axis at right angles thereto whereby said angularity indicating means fixed to said first named base is adapted to indicate the angularity of said blade relative to said straight edge and marking means guidable by said guiding blade whereby a line may 105 be scribed on irregular surfaces in a plane parallel to said guiding blade.
8. In a universal square, a base having a hole therein, one edge of said base being straight, a post having a trunnion rotatable in said hole, a flange on said post above 110 said trunnion adapted to have bearing on said base, a ring secured on said base about said flange, and having a rabbet therein in which said flange is rotatably retained, means whereby said post and flange are clamped in adjusted position, there being 115 indicating marks on said ring, and a coacting indicating mark on said flange, said post having a slot therein at right angles to the plane of rotation thereof, a guiding blade 120 rotatably adjustable in said slot and comprising an arm having a slot therein, and a depending plate integrally formed therewith, means for holding said guiding blade 125

in adjusted positions relative to said post, and a marking means adapted to be guided by said guiding means.

9. In a universal square, a guiding plate, 5 a pair of pivotally connected arms, a segment secured to one of said arms, the other of said arms having a slot therein in which said segment is slidable, means whereby said segment is clamped in said slot to hold said

arms in adjusted position, a guide plate secured to one of said arms adapted to slidably contact said guiding blade, a bearing in the other of said arms, a marking point longitudinally adjustable in said bearing, and means for holding said marking point 15 in adjusted position.

LOUIS APRILE.
